UNITED STATES PATENT OFFICE.

STEPHAN CZEILER, OF ARAD, AUSTRIA-HUNGARY.

LOCK.

SPECIFICATION forming part of Letters Patent No. 601,371, dated March 29, 1898.

Application filed September 25, 1897. Serial No. 653,020. (No model.)

To all whom it may concern:

Be it known that I, STEPHAN CZEILER, cabinet-maker, of Arad, in the Empire of Austria-Hungary, have invented new and useful Improvements in Door and Similar Locks, of which the following is a specification.

My invention has for its object an improved lock, the bolt of which, operated by turning the handle-knob, serves at the same time for locking the door or the like by being caused by means of keys to enter the keeper. This lock can be fitted to either right or left hand doors.

In the drawings, Figures 1 and 2 are side and front views of a lock which is fitted to right-hand doors. Figs. 3 and 4 show a side and front view of a lock which is fitted to left-hand doors. Figs. 5, 6, and 7 are details of this lock.

The mechanism is contained in a casing A, in which a lever or cam a is provided having a square aperture a^2 for receiving the handle and carrying two pins a^4 a^5 at its opposite ends, one pin a^4 being normally raised by a spring a^5 , arranged around the handle-sprocket a^3 and resting with its other end against a pin k , secured to the lock-casing A, whereby the handle is returned to its normal position when it is released. The movement of the handle beyond this normal position is prevented by the hinge-joint b' of two levers b c , which are acted upon by the second pin a^5 coming in contact with the casing of the lock. This pin a^5 further serves to cause the bolt e to return within the casing when the knob is turned, said pin a^5 causing the lever b to turn about its pivot s , secured to the casing, whereby the second lever c , connected to it by a pin or hinge-joint b' , is caused to move backward. This movement of the lever, owing to its engagement with a tooth or stop e' on the bolt e , Fig. 5, withdraws the bolt e into the casing. As soon as the handle is released the bolt e is returned into its normal position by the head l^2 of a spring n , secured to a projection or pin l on the casing. This normal position of the bolt e , Fig. 1, shows the same in full lines, and is secured by a tumbler d , mounted on a pivot-pin e^5 of the bolt, being pressed against a projection p of the casing by the head l^2 of the spring n referred to acting on the end of said tumbler. The projection p also serves

for guiding the bolt e by engaging with a groove e^6 therein. When the bolt e is in this first normal position, it can be withdrawn into the casing by the handle as well as by the key, and the door thus opened. When the key is turned in direction I, it engages with a tooth e^2 of the bolt and pushes the latter back into the casing. If, however, the key is turned in the opposite direction II, then the key raises the tumbler d against the head of the spring l^2 till its tooth d' is raised above the projection p and the bolt e is thrown forward by the spring l^2 . Then the bolt is in its second locked position, (dotted lines, Fig. 1,) in which the face d^2 of the tumbler d is pressed against the projection p by the head of the spring l^2 . In this position of the bolt the door is locked, and it can be opened only by means of the key. This position is secured by the tumbler d being in a higher position and holding the lever c , engaging with it, also in a higher position than before, so that if the knob were now turned said lever instead of moving backward would only be pressed against the fixed projection k , against which the spring of the handle-lever presses. If it is desired to open the door, the key must be turned in direction I, whereupon the tumbler d will be raised till its tooth d' is raised above the projection p , with which it was engaged. If the key is turned still farther, it will press the bolt e back against the spring-head l^2 till the tooth d' of the tumbler d falls behind the projection p under the influence of the pressure of the spring-head l^2 , at which moment the tooth l^2 is released, and the spring-head l^2 holds the bolt e in its first normal position. If the key is farther turned in direction I, the key will fulfil the function of the handle, and the bolt will be completely withdrawn, Fig. 3, dotted lines.

The bolt can be fitted both to right and left hand doors by making the bolt e symmetrical on either side of its axis x x , Fig. 7. If the bolt e is turned around, together with the front plate B, the locking-face e' of the bolt e , if it was before on the left-hand side, will now be on the right-hand side, and if it was used for a right-hand door it can now be used for a left-hand one.

When reversing the bolt e , the tumbler d must be removed from the bolt e and turned

also in order that the bolt *e* may retain its original position. The function of the teeth *e' e² e³ e⁴* is interchanged, the original upper teeth *e' e⁴* fulfilling the function of the original lower teeth *e² e³*, and vice versa.

Having thus described my invention, what I claim is—

1. In combination, the casing, the bolt sliding therein, the projection from the casing engaging a slot in the bolt to guide the same, the tumbler pivoted to said bolt and having shoulders adapted to engage said projection to hold it in either an advanced or a semiretracted position, the spring bearing against the rear end of the tumbler, the cam adapted to receive the knob-spindle, the rocking lever operated by said cam, and the spring-pressed arm connected to said lever and engaging a projection on the bolt, substantially as described.
2. In combination, the casing, the bolt sliding therein, the projection from the casing

engaging a slot in the bolt to guide the same, the tumbler pivoted to said bolt and having shoulders adapted to engage said projection to hold it either in an advanced or a semiretracted position, the knob-spindle, the cam carried thereby, the rocking lever operated from the cam, the link connected at one end to said rocking lever and having its opposite end bearing against the upper side of the bolt and engaging a projection carried thereby, and the spring having one end bearing against the rear end of the tumbler, the opposite end bearing on the upper side of the said link, and having its intermediate portion coiled around a projection on the casing, substantially as described.

In witness whereof I have hereunto set my hand in presence of two witnesses.

STEPHAN CZEILER.
